(57) **CLAIM**

The ornamental design for a door lever shank, as shown and described.

DESCRIPTION

FIG. 1 is an isometric view of a door lever shank showing our new design;

FIG. 2 is a front view of FIG. 1;

FIG. 3 is a bottom view of FIG. 1;

FIG. 4 is a rear view of FIG. 1;

FIG. 5 is a top view of FIG. 1;

FIG. 6 is a right side view of FIG. 1; and,

FIG. 7 is a left side view of FIG. 1.

The broken-line disclosure in the views is for illustrative purposes only and forms no part of the claimed design.
